United States Patent Office

Des. 222,451
Patented Oct. 26, 1971

222,451

FURNITURE SEAT

Thomas Larry Lamb, Toronto, Ontario, Canada, assignor
to Thomas Lamb & Associates Limited, Toronto, Ontario, Canada

Filed Apr. 13, 1970, Ser. No. 22,402

Term of patent 14 years

Claims priority, application Canada Oct. 17, 1969

Int. Cl. D6—02

U.S. Cl. D15—1

FIG. 1 is a front perspective view of the furniture seat showing my design;

FIG. 2 is a side view of the furniture seat;

FIG. 3 is a rear perspective view of the furniture seat of my design; and

FIG. 4 is a front perspective view of an alternate embodiment of a furniture seat showing my design.

The side of the furniture seat not shown is a mirror image of the side shown in FIG. 2.

I claim:

The ornamental design for a furniture seat, as shown and described.
